(57) CLAIM

The ornamental design for a surface ornamentation for apparel, bottle, and fob, as shown and described.

DESCRIPTION

FIG. 1 is a left view of a surface ornamentation for apparel, bottle, and fob, shown on an unclaimed footwear environment;

FIG. 2 is a right view thereof;

FIG. 3 is a front view of a surface ornamentation for apparel, bottle, and fob, shown on an unclaimed shirt environment;

FIG. 4 is a front view of a surface ornamentation for apparel, bottle, and fob, shown on an unclaimed jacket environment;

FIG. 5 is a front view of a surface ornamentation for apparel, bottle, and fob, shown on an unclaimed pants environment;

FIG. 6 is a front view of a surface ornamentation for apparel, bottle, and fob, shown on an unclaimed cap environment;

FIG. 7 is a front view of a surface ornamentation for apparel, bottle, and fob, shown on an unclaimed hat environment;

FIG. 8 is a front view of a surface ornamentation for apparel, bottle, and fob, shown on an unclaimed bottle environment; and,

FIG. 9 is a front view of a surface ornamentation for apparel, bottle, and fob, shown on an unclaimed fob environment. The broken line showing of the footwear, shirt, jacket, pants, hat, bottle, and fob illustrates alternate environments and forms no part of the claimed design.

A portion of the disclosure of this patent document contains registered trademarks. The trademark owner has no objection to reproduction of the patent document or the patent disclosure as it appears in the U.S. Patent and Trademark Office record but reserves all other trademark rights. The DRY STEPPERS trademarks (Reg. U.S. Pat. No. 5,428,379 and Reg. U.S. Pat. No. 5,428,380) forming part of the claimed design are registered trademarks of DRYSTEPERS, LLC.
